WASHING MACHINE

Johannes B. Kessel, Chicago, Ill.

Substitute for abandoned application Serial No. 153,461, July 14, 1937. This application January 12, 1939, Serial No. 250,592

13 Claims. (Cl. 259—95)

This application is a substitute application for abandoned application Serial #153,461 filed July 14, 1937.

- This invention relates to improvements in machines particularly adapted, though not necessarily limited in use, for washing dishes, clothes, or other articles and which may be employed with equal efficiency as a mixing machine for mixing liquids, and one of the objects of the invention is 5 to provide an improved machine of this character in which the usual agitator that projects into the liquid to agitate the same, and which also engages and agitates the articles being cleaned, is dispensed with. 10
- A further object is to provide a machine of this character wherein there is employed a suction fan or device disposed above the liquid and the articles being cleaned, and which operates to draw up the liquid by suction and then deliver the 15 same with considerable force and pressure against the sides of the liquid holding receptacle and also against the articles, thereby causing a violent agitation and circulation of the liquid.

A further object is to provide a machine of this 20 character which will be of a simple, durable, cheap and compact construction and effective and efficient in operation.

To the attainment of these ends and the accomplishment of other new and useful objects 25 as will appear, the invention consists in the features of novelty in substantially the construction, combination and arrangement of the several parts, hereinafter more fully described and claimed and shown in the accompanying drawing illustrating this invention, and in which—

Figure 1 is a view partly in elevation and partly in vertical section of a machine of this character constructed in accordance with the principles of this invention.

Figure 2 is a bottom plan view of the top or cover of the receptacle.

Figure 3 is an enlarged detail sectional view of a portion of the cover or receptacle and the suction creating device.

Figure 4 is a detail perspective view of the member which may be employed for preventing swirling of the liquid.

Referring more particularly to the drawing, the numeral 10 designates generally a receptacle of any desired size and configuration and constructed of any suitable material. The receptacle is provided with an open top that is closed by means of a closure 11. This closure may be of any desired size and configuration and constructed of any suitable material, but is preferably of a dome shape configuration. The closure is adapted to be held in position upon the receptacle 10 in any suitable manner, preferably to be detachable therefrom.

To that end, the lower or open portion of the

closure is adapted to telescope into the top of the receptacle 10 as at 12 and a bead or flange 13 may be provided on the closure to limit the extent to which the closure will telescope into the receptacle and to form a fluid tight joint to prevent the liquid from splashing or being forced out of the receptacle. 5

Mounted upon the closure 10 is a motor 14, the rotor of which operates upon a vertical axis and the shaft 15 of the rotor projects through a suitable opening in the top of the closure 11 and extends for a substantial distance into the closure. The opening in the closure through which the shaft 15 projects is preferably only slightly larger than the diameter of the projecting portion of the shaft. 10

The motor may be encased in a suitable housing 16 removably secured to the closure in any desired or suitable manner, preferably by means of bolts 17 passing through the closure from the 20 inside thereof and entering the wall of the housing 16, thereby rendering it possible, if desired, to detach the motor and housing 16 from the closure, at the same time concealing the fastening bolts 17. 25

A suction fan is secured to the shaft 15 within the closure 11. This fan may be of any desired or suitable construction but preferably consists of an apertured body 18 preferably in the form of a disc, and secured to the body 18 are blades 19 which preferably terminate short of the diametric center of the disc to form a suction space 20. The disc or body portion 18 is preferably secured to a hub 21 into which the shaft 15 projects and the two are secured together in any 30 suitable manner such as by means of a screw or bolt 22 to cause the same to rotate in unison, and the disc or body portion 18 is preferably disposed a short distance from the face of the crown of the closure 11 to form an air circulation space 35 23 therebetween. 40

In order to facilitate handling of the closure suitable handles 24 may be provided thereon.

Obviously the motor may be driven from any suitable source of power, such as by means of 45 conductors (not shown), which may be connected to any suitable source of supply of current.

In use, the desired amount of liquid is placed within the container or receptacle 10 together with the articles to be cleaned. If, however, the 50 machine is to be employed for mixing liquids, the liquids to be mixed are put into the receptacle 10.

The closure 11 is then placed in position and the motor operated to rotate the suction creating 55 device.

The speed of rotation of the suction creating device will create a suction within the machine and will raise a portion of the liquid toward the suction creating device and at the same time the 60

pressure created by the suction device will deflect or cause the liquid to be discharged or delivered with considerable force or pressure downwardly against the sides of the closure as well as downwardly into the receptacle 10 causing a violent circulation of air and liquid within the machine. The disc or body portion 18 of the suction creating device acts as a separator for the air and liquid, the air being drawn up into the space 20 and through the apertures or perforations in the disc or body portion 18 into the space 23 from where it will flow outwardly toward the wall of the closure and will be directed downwardly and back again into the receptacle 10.

15 Thus it will be seen that with this construction the liquid will have a circulation somewhat in the path of movement as indicated by the arrows marked "W", while the air will have a circulation somewhat in the paths indicated by the 20 arrows marked "A".

If desired, and in order to prevent the formation of eddies or a rotation of the liquid in the receptacle 10, any suitable means may be provided for breaking up or preventing such 25 circulation.

A simple and efficient means embodies an element as shown in Figure 4. This element may be of any desired or suitable construction and of any desired height and constructed of any 30 suitable material, and preferably comprises an annular body portion 25 having radially projecting wings or ribs projecting from the periphery thereof. These wings or ribs, any number of which may be provided, are laterally spaced from 35 each other, and the element is placed within the receptacle 10 to rest upon the bottom thereof. The element is of such a length that the extremities of the blades or wings 26 will be disposed in close proximity to the wall of the receptacle 10 so as to prevent the same from rotating bodily in the receptacle.

It will be manifest that with a device of this character the same may be placed upon a stove or over a heating element so that the contents 45 of the receptacle may be heated during the operation of the machine.

While the preferred form of the invention has been herein shown and described, it is to be understood that various changes may be made 50 in the details of construction and in the combination and arrangement of the several parts, within the scope of the claims, without departing from the spirit of this invention.

What is claimed as new is:

55 1. In a machine of the character described, a single container having imperforate side and bottom walls and in which container the liquid and the articles to be cleaned are directly confined, a closure for the container sealing it against admission of air, a suction creating device housed 60 within the machine and supported by said closure, and actuating means for the said suction creating device, supported by the closure outside of the machine and operatively connected with said suction creating means through said closure, substantially the entire area of the suction creating device and of the container below and in proximity to the suction creating device being free from obstructions.

70 2. In a machine of the character described, a single container having imperforate side and bottom walls and in which container the liquid and the articles to be cleaned are directly confined, a closure for the container sealing it against admission of air, a suction creating device housed 75

within the machine and supported by said closure, and actuating means for the said suction creating device, supported by the closure outside of the machine and operatively connected with said suction creating means through said closure, 5 said suction creating device comprising a fan rotating about an upright axis, substantially the entire area of the suction creating device and of the container below and in proximity to the suction creating device being free from obstruc- 10 tions.

3. In a machine of the character described, a single container having imperforate side and bottom walls and in which container the liquid and the articles to be cleaned are directly confined, 15 a dome shaped closure therefor sealing the container against admission of air, a suction fan disposed within and in close proximity to the crown of said closure, and a motor supported by and outside of said closure, said motor embody- 20 ing a shaft extending through said closure and to which shaft said fan is connected to rotate about an upright axis, said fan being of a diameter considerably less than the interior diameter of said dome, substantially the entire area of said 25 fan and of the container below in proximity to the fan being free from obstructions.

4. In a machine of the character described, a single container having imperforate side and bottom walls and in which container the liquid and the articles to be cleaned are directly confined, 30 a dome shaped closure therefor sealing the container against admission of air, a suction fan disposed within and in close proximity to the crown of said closure, and a motor sup- 35 ported by and outside of said closure, said motor embodying a shaft extending through said closure and to which shaft said fan is connected to rotate about an upright axis, said fan being of a diameter considerably less than the interior di- 40 ameter of said dome, the body of said fan comprising a perforated plate and said blades being disposed at right angles to said plate and terminating considerably short of the diametric center of the plate, whereby the fan will create a suction 45 adjacent its axis and a pressure adjacent the periphery thereof, substantially the entire area of said fan and of the container below in proximity to the fan being free from obstructions.

5. In a machine of the character described, a 50 single container having imperforate side and bottom walls and in which container the liquid and the articles to be cleaned are confined, a dome shaped closure therefor sealing the container against admission of air, a portion of the closure 55 telescoping with the container, a suction creating fan disposed within and adjacent the crown of said closure and of a diameter considerably smaller than the diameter of the encompassing portion of the closure, said fan rotating about an upright axis, and means for rotating said fan from the outside of said closure, whereby the liquid and air will be drawn up by suction, separated and the liquid discharged adjacent the container wall while the air and liquid are main- 60 tained in the same chamber with the articles being cleaned.

6. In a machine of the character described, a single container having imperforate side and bottom walls and in which container the liquid and 70 the articles to be cleaned are directly confined, a closure for the container sealing the same against the admission of air, means within the machine disposed above a liquid level therein and operating when actuated to create a suction, lifting a 75

portion of the fluid in the form of a spray, and creating a pressure forcing the fluid downwardly and back into the container, and means for actuating the first recited means from the outside 5 of the machine, the first said means embodying a fan device rotatable on a vertical axis, and comprising a body plate and blades arranged at right angles thereto, said blades disposed within the confines of the periphery of the plate and 10 terminating considerably short of the diametric center of the plate, substantially the entire area of the said suction creating means and of the container below and in proximity to the suction means being free from obstructions, the liquid 15 being maintained and circulated within the confines of the container.

7. A machine of the character described embodying a single container having an open top and in which container the liquid and the articles 20 to be cleaned are directly confined, a closure for the container sealing the same against admission of air, a suction creating device housed within the machine and supported by said closure above the liquid level, said suction creating device provided 25 with imperforate blades, and actuating means for said suction creating device also supported by said closure, substantially the entire area of said suction creating device and of the container below and in proximity to the said suction creating 30 device being free from obstructions.

8. A machine of the character described embodying a single container having an open top and in which container the liquid and the articles to be cleaned are directly confined, a closure for 35 the container sealing the latter against admission of air, a suction creating device housed within the machine and supported by said closure above the liquid level and having a constant direction of movement, substantially the entire area 40 of the suction creating device and of the container below and in proximity to the suction creating device being normally unobstructed, actuating means for said suction creating device also supported by said closure, said suction 45 creating device operating to draw up and separate air and liquid and discharge the liquid back against the liquid in the container tending to impart a swirling movement to the latter, and means within the container for maintaining the 50 liquid in the container against a whirling movement, the last said means being freely removable from the container.

9. A machine of the character described embodying a single container forming a chamber having 55 an open top and in which chamber the liquid and the articles to be cleaned are directly confined and supported upon a common bottom, a closure for the chamber sealing the same against the entrance of air, a suction creating device housed 60 within the machine and supported by said closure above the liquid level, substantially the entire area of the suction creating device and of the container below and in proximity to the suction creating device being free from obstruction and 65 actuating means for said suction creating device also supported by said closure, the fluids circulated by the operation of said suction creating device being at all times maintained within the said chamber.

70 10. In a machine of the character described, a container in which the articles to be cleaned and the liquid are directly confined, a closure for the

container sealing the latter against entrance of air, a suction fan supported by the closure above the liquid level and provided with imperforate blades, means for rotating the fan, substantially the entire area of said fan and of the container 5 below and in proximity to the fan being free from obstructions, said fan having a constant direction of rotation and operating to draw the liquid into the center thereof to form a vortex against the articles being cleaned, and also operating to discharge the liquid from said vortex radially and against the wall of the container back against the liquid in the container to create a swirling movement of the liquid.

11. In a machine of the character described, a 15 container in which the liquid and the articles to be cleaned are directly confined, a dome shaped closure for the container sealing the latter against entrance of air, a suction creating device disposed within the dome and supported thereby, 20 said dome and container for substantially the entire area of the suction creating device and of the container below and in proximity to the suction creating device being free from obstruction, and actuating means for the suction creating device 25 supported by and on the outside of the machine, said suction device embodying a fan having a constant direction of movement rotatable on a vertical axis, and of a diameter considerably less than the diameter of the said dome, the 30 blades of the fan being imperforate and the central portion thereof being removed, whereby upon rotation of the fan a vortex of the liquid will be formed and the liquid will be forced by pressure radially from the fan and against the 35 dome.

12. For use in a washing machine, a dome shaped closure sealing the same against entrance of air, a fan centrally mounted in the closure in close proximity to the dome and completely 40 housed thereby, said fan being rotatable on an upright axis, said fan being of a diameter considerably less than the adjacent portion of the dome, and means mounted on the outside of the dome for rotating the fan, said fan having imperforate blades, the ends of the blades adjacent 45 the axis of the fan being removed, whereby when said fan is operated a suction will be created at the inner periphery of the fan and a blast at the outer periphery and against the wall of the 50 dome.

13. In a machine of the character described, a container open only at its top, a closure for the container sealing the container against entrance of air, a suction creating device disposed within 55 the container and supported by said closure, actuating means for said suction creating device and supported by said closure outside of said container and operatively connected with said suction creating device through said closure, substantially the entire area of the suction creating device and of the container below the suction creating device and in proximity to the latter being free from obstructions whereby upon operation of said suction creating device air and liquid 60 will be drawn up and separated thereby, the liquid being directed downwardly and outwardly back again toward the supply of liquid in the container causing a swirling movement to be imparted to the liquid in the container.
